Walter J. McAver, 131st St., and 82nd Ave.,
Orland Park, Ill.

Filed Mar. 28, 1960, Ser. No. 59,886

Term of patent 14 years

(Cl. D1—7)

Figure 1 is a side elevational view of a combined home-owner's name plate sign and mail box, showing my new design, the opposite side being substantially the same as the side shown.

Fig. 2 is a front elevational view thereof.

Fig. 3 is a top plan view thereof.

Fig. 4 is a horizontal cross-sectional view thereof taken on the line 4—4 of Fig. 1.

I claim:

The ornamental design for a combined home-owner's name plate sign and mail box, as shown and described.
